UNITED STATES PATENT OFFICE.

GEORGE J. STREIB, OF MOUNT VERNON, NEW YORK.

DESIGN FOR A RADIOCABINET.

Application filed May 16, 1925. Serial No. 13,461. Term of patent 7 years.

To all whom it may concern:

Be it known that I, GEORGE J. STREIB, a citizen of the United States, residing at 24 Harrison St., Mount Vernon, in the county of Westchester and State of New York, have invented a new, original, and ornamental Design for Radiocabinets, of which the following is a specification, reference being had to the accompanying drawing, forming part thereof.

The figure is a perspective view of a radio cabinet, showing my new design.

I claim:

The ornamental design for a radiocabinet, as shown.

24 Harrison St., Mt. Vernon, N. Y.

GEORGE J. STREIB.
